CLAIM

The ornamental design for a bottle convertible to a glass, as shown and described.

DESCRIPTION

FIG. 1 is a top perspective view illustrating a bottle convertible to a glass in a bottle configuration;

FIG. 2 is an exploded top perspective view illustrating the bottle convertible to the glass in the bottle configuration with a base removed;

FIG. 3 is a top perspective view illustrating the bottle convertible to the glass in a glass configuration;

FIG. 4 is a top perspective side view illustrating the bottle convertible to the glass in the glass configuration rotated 180 degrees from the view shown in FIG. 3 and showing an inner seal partially removed;

FIG. 5 is an enlarged side view illustrating the bottle convertible to the glass in the bottle configuration, each side view being identical;

FIG. 6 is an enlarged side view illustrating the bottle convertible to the glass in the glass configuration, each side view being identical;

FIG. 7 is an enlarged top view illustrating the bottle convertible to the glass in the bottle configuration;

FIG. 8 is an enlarged bottom view illustrating the bottle convertible to the glass in the bottle configuration;

FIG. 9 is an enlarged top view illustrating the bottle convertible to the glass in the glass configuration;

FIG. 10 is an enlarged bottom view illustrating the bottle convertible to the glass in the bottle configuration; and,

FIG. 11 is a bottom perspective view illustrating a bottle convertible to a glass in a bottle configuration.
